UNITED STATES PATENT OFFICE.

ANDREW JACKSON, OF LEADVILLE, COLORADO.

BREAD-SLICER.

1,033,406.

Specification of Letters Patent. Patented July 23, 1912.

Application filed November 21, 1910. Serial No. 593,493.

To all whom it may concern:

Be it known that I, ANDREW JACKSON, a citizen of the United States, residing at Leadville, in the county of Lake and State of Colorado, have invented certain new and useful Improvements in Bread-Slicers, of which the following is a specification.

This invention relates to improvements in bread or other slicers, and has particular reference to a device of this character which will feed the loaf forward to the cutting knife, step by step.

Another object is to provide a device of this character, which will hold the loaf from the opposite side to the knife, and impart a slight pressure thereto.

These and other objects will be apparent from the following description, and with particular reference to the accompanying drawings forming a part of this specification, and in which,

Figure 1 is a side elevation of the device, Fig. 2 is an end elevation of the same, Fig. 3 is a top plan view of the device, Fig. 4 is a transverse section on the line 4—4 of Fig. 3.

Referring now particularly to the drawings, it will be seen that the invention comprises an elevated platform 1, which is divided by a transverse slot 2, to provide the receiver 3 at one end thereof. On one side of the platform, and running longitudinally thereof, is a guiding flange 4, and below said flange is a ratchet bar 5, connected at one end to a pusher or follower 6, having the vertical spikes 6' which are adapted to pierce a loaf 7 of bread or other material to be cut. The follower comprises a straight flat strip of metal 4' which is adapted to lie transversely on the platform 1, and is bent around the flange 4 as at 5'. The lower end 7' of the strip 4' extends below the flange and is secured to one end of the ratchet bar 5, so that the bar and follower move in unison. Suitably secured to the platform 1 and raised thereabove are the standards or supports 8 and 8' in the upper ends of which is journaled a shaft 9, which is disposed in parallel relation to the platform. Mounted rigidly on one end of the shaft is a curved knife 10, and on the opposite end of the shaft is a crank handle 11, by means of which the shaft is rotated to cause the knife to revolve through the above-mentioned slot 2. On the shaft 9, and adjacent the crank, is a disk 12, on one face of which and adja-

cent the periphery thereof, is formed a cam ledge 13. Mounted pivotally near its central portion is a curved arm 14, having its nose 15 engaging in the ratchet teeth of the bar 5, and a reduced portion on its upper end adapted to engage on the ledge 13. This ledge 13 extends circumferentially on the disk, and is higher at a point 16 than at a point 17, so that the said lever or arm 14 will be rocked as the surface of the ledge rides over the upper end of said arm. Thus in every revolution of the disk 12, the arm 14 is rocked forward and backward once, which causes the nose 15 to engage with the ratchet bar to advance the follower one step, which carries the loaf forward over the slot 2 for the next cut. In the receiving tray 3, and so positioned that it will engage successively with the teeth of the ratchet bar, is a spring pressed pawl 18, which prevents the said ratchet bar moving backward.

The material to be cut is placed on the platform 1 in engagement with the spikes 6' and pushed forward until the loaf is over the slot 2, and the knife rotated by means of the handle 11. This cuts a slice from the loaf, and at the same time the disk 12 engaging with the upper end of the arm 14 moves the same back and forth and advances the loaf another step under the knife. Pivotally mounted on the standard 8' is an arm 19, but moving in a path transversely to that of the other arm, and adapted to engage the upper face of the loaf. A disk 12' is eccentrically mounted on the opposite end of the shaft 9, and formed in the peripheral face thereof is an undercut groove or slot 20, which is adapted to receive therein, the T-shaped head of the extension 19' of the arm 19. When the disk 12 is revolved, the arm 19 is rocked backward and forward, toward and away from the loaf to form a firm backing against which the loaf is held while the knife is in the act of cutting. The arm 19 moves away from the loaf when the knife has passed through the loaf, and advances thereagainst when the knife again advances to the cutting point. The lower portion of the arm 19 is somewhat wider than the upper portion, and engages against the loaf back of the knife. The slices of the material, when cut, readily fall into the receiving tray 3.

On one side of the platform 1 is secured a handle 22, by means of which the entire device may be readily carried.

It will thus be seen that the material is effectively cut and held while being cut. Also the loaf is advanced step by step to present a fresh portion to be cut.

5 What is claimed is:

A slicing machine comprising a platform upon a suitable support, a rack bar slidably mounted upon the support, one edge of the platform projecting beyond the edge of the support to form a guide edge, a follower secured to one end of the rack bar and curved intermediate its ends for engagement over the guide edge of the platform, said follower having a portion thereof resting upon the platform and adapted for movement longitudinally thereover, said follower having article engaging means for engage-

ment with an article to move the same longitudinally upon the platform upon movement of the rack bar, article slicing mechanism, and means for operating the rack bar to feed the article along the platform and at the same time to operate the slicing mechanism for slicing the article, and means for automatically engaging the article to retain the same in position during the operation of slicing the said article.

In testimony whereof I affix my signature, in the presence of two witnesses.

ANDREW JACKSON.
